STEAM GENERATING FURNACE

Gustav A. Rehm, Worcester, Mass., assignor to
Riley Stoker Corporation, Worcester, Mass., a
corporation of Massachusetts

Application November 9, 1934, Serial No. 752,320

6 Claims. (Cl. 122—235)

This invention relates to steam generating furnaces, and more particularly to furnaces of the type having water tubes associated with the furnace walls to absorb radiant heat from the combustion flame and additional water tubes located in the path of the gases after they leave the combustion chamber.

One form of boiler in common use today is known in the art as a "cross-drum" boiler, and comprises a bank of inclined water tubes connected to headers at each end, the headers being connected by circulating tubes to a transverse horizontal steam-and-water drum. In boilers of this type the circulation is seriously restricted by lack of suitable provision for the release of the steam from the tubes, and this condition is aggravated if water wall tubes are arranged to deliver additional steam into the boiler headers.

It is accordingly one object of the invention to provide a steam generating furnace having a steam boiler and water walls so constructed and arranged that the steam from the water walls will be effectively released without disturbing the boiler circulation.

It is a further object of the invention to provide a steam generating furnace having a steam boiler of the cross-drum type, together with water walls so constructed and arranged as to deliver steam directly to the boiler drum without disturbing the boiler circulation.

It is a further object of the invention to provide a steam generating furnace having a steam boiler of the cross-drum type, together with water walls and slag screen tubes below the boiler tubes, the parts being so constructed and arranged as to avoid any disturbance to the boiler circulation as a result of steam released from the water walls and slag screen tubes.

With these and other objects in view, as will be apparent to those skilled in the art, the invention resides in the combination of parts set forth in the specification and covered by the claims appended hereto.

Referring to the drawings illustrating one embodiment of the invention, and in which like reference numerals indicate like parts,

Fig. 1 is a longitudinal section through a steam generating furnace, the section being taken on the line 1—1 of Fig. 2; and

Fig. 2 is a section on the line 2—2 of Fig. 1. In the drawings I have shown a steam boiler comprising a lower rear group of upright headers 10 and an upper front group of upright headers 11, the headers of the two groups being connected by a bank of upwardly and forwardly inclined

water tubes 12. A transverse horizontal steam-and-water drum 14 is mounted above the rear headers 10 and is connected to these headers by vertical down-comer tubes 15. The drum is connected to the upper portions of the front headers 11 by means of horizontal tubes 16. Walls 18 form a furnace chamber beneath the boiler, and baffles 19 direct the hot gases as they flow from the furnace chamber across the tube bank 12 and thence to a gas outlet 20 adjacent to the drum 14. The boiler as so far described is of well-known construction, and many are in use throughout the country.

In order to protect the furnace walls and at the same time obtain increased steam generation through the absorption of radiant heat, it is desirable to provide water tubes at the boundaries of the combustion chamber. It is also desirable, when burning certain slag forming fuels, to provide a row of comparatively widely spaced water tubes below the boiler tubes to chill the slag particles carried in suspension in the hot gases and prevent them from adhering to the boiler tubes. The upward flow of steam from the boiler tubes is seriously restricted by reason of the small flow area afforded by the front boiler headers 11, and it is therefore important to avoid the release of additional steam to these headers.

In the preferred construction illustrated I have provided a row of upright water wall tubes 22 at the rear of the furnace, the lower ends of the tubes being connected to a transverse header 23, and their upper ends being connected to a transverse header 24 located near the lower ends of the rear boiler headers 10. The lower header 23 is supplied with water from the boiler, preferably by means of a row of down-comer tubes 25 leading from the lower ends of the rear boiler headers. A row of slag screen water tubes 27 extends forwardly and upwardly from the upper header 24, the front ends of these tubes being connected to a transverse header 28 located adjacent to the lower ends of the front boiler headers 11. The slag screen tubes are comparatively widely spaced, both from each other and from the boiler tubes. A pipe or conduit 29 extends upwardly and rearwardly from each end of the header 28, and these pipes connect with the ends of a transverse header 31 located adjacent to the lower front surface of the boiler drum 14. This header 31 is connected to the boiler drum by means of a row of tubes 32.

At each side of the combustion chamber I have shown a row of upright water tubes 34 with their lower ends connected to headers 35 and their upper ends connected to headers 36. The lower

headers 35 are supplied with water from the lower rear water wall header 23 by means of tubes 38. The upper headers 36 are connected to the pipes 29 by means of rows of tubes 39.

5 At the front of the combustion chamber I have shown a row of upright water tubes 41 with their lower ends connected to a transverse header 42 and their upper ends connected to the header 28. The ends of the header 42 are connected to the lower rear water wall header 23 by means of pipes 43.

10 The operation of the invention will be apparent from the above disclosure. A suitable fuel, such as pulverized coal, is burned in the combustion chamber, and the hot gases flow in contact with the boiler tubes 12 and escape through the outlet 20. Water circulates downwardly from the drum 14 through the tubes 15 to the headers 10, forwardly through the tubes 12 to the headers 11, and 15 thence rearwardly through the tubes 16 to the drum, where the steam is liberated and withdrawn to a place of use. Water also flows from the headers 10 downwardly through the tubes 25 to the header 23, and upwardly through the tubes 22, header 24, tubes 27, header 28, pipes 29, header 31 and tubes 32 to the drum. The lower side water wall headers 35 receive water from the header 23 through the tubes 38 and this water flows upwardly through the tubes 34, headers 36 and 20 tubes 39 to the pipes 29. The lower front water wall header 42 receives water from the header 23 through the pipes 43, and this water flows upwardly through the tubes 41 to the header 28.

25 The water wall tubes 22, 34 and 41 not only protect the furnace walls, but they also absorb radiant heat at a high rate and thus generate large quantities of steam. The slag screen tubes 27 cool the upwardly flowing gases sufficiently to prevent slag carried in suspension in the gases 30 from adhering to the boiler tubes. The construction is comparatively simple and inexpensive, and there is ample flow area for the release of steam generated in the water walls and slag screen tubes without interfering with the boiler circulation.

35 Having thus described my invention, what I claim as new and desire to secure by Letters Patent is:

1. A steam generating furnace comprising a lower rear group of upright headers, an upper front group of upright headers, a bank of upwardly and forwardly inclined water tubes connecting the groups of headers, a transverse steam-and-water drum arranged to supply water to the lower headers and to receive steam from the upper headers, a transverse header located adjacent to the lower ends of the upper headers, a row of steam generating tubes arranged to deliver steam to the transverse header, means including pipes extending upwardly and rearwardly from the ends of the transverse header to deliver steam therefrom to the drum, a longitudinal header beneath each pipe, upright water wall tubes at each side of the furnace connected at their upper ends to the longitudinal headers, and a row of spaced tubes connecting each longitudinal header with the upwardly and rearwardly inclined pipe thereabove.

2. A steam generating furnace comprising a lower rear group of upright headers, an upper front group of upright headers, a bank of upwardly and forwardly inclined water tubes connecting the groups of headers, a transverse steam-and-water drum arranged to supply water to the lower headers and to receive steam from the upper headers, a transverse header located adjacent

to the lower ends of the upper headers, a row of steam generating tubes arranged to deliver steam to the transverse header, pipes extending upwardly and rearwardly from the ends of the transverse header, means including water wall tubes at each side of the furnace arranged to deliver steam to said pipes, a second transverse header connecting the rear ends of the pipes, and tubes connecting the second transverse header with the drum.

3. A steam generating furnace comprising a lower rear group of upright headers, an upper front group of upright headers, a bank of upwardly and forwardly inclined water tubes connecting the groups of headers, a transverse steam-and-water drum arranged to supply water to the lower headers and to receive steam from the upper headers, a transverse header located adjacent to the lower ends of the upper headers, a row of upwardly and forwardly inclined slag screen tubes connected at their upper ends to the transverse header, means including pipes extending upwardly and rearwardly from the ends of the transverse header to deliver steam therefrom to the drum, and means including water wall tubes at each side of the furnace arranged to deliver steam to said pipes.

4. A steam generating furnace comprising a bank of inclined water tubes connected at each end to upright headers, a transverse steam-and-water drum arranged to supply water to the lower headers and to receive steam from the upper headers, a transverse header located adjacent to the lower ends of the upper headers, a second transverse header located adjacent to the lower ends of the lower headers, inclined slag screen tubes connecting the two transverse headers, upright water wall tubes connected at their upper ends to the second transverse header, a third transverse header adjacent to the drum and connected thereto by a row of tubes, pipes connecting the respective ends of the first and third transverse headers, a longitudinal header beneath each pipe, upright water wall tubes connected at their upper ends to the longitudinal headers, and tubes connecting the longitudinal headers with the pipes thereabove.

5. A steam generating furnace comprising a bank of inclined water tubes connected at each end to upright headers, a transverse steam-and-water drum arranged to supply water to the lower headers and to receive steam from the upper headers, a transverse header located adjacent to the lower ends of the upper headers, a second transverse header located adjacent to the lower ends of the lower headers, inclined slag screen tubes connecting the two transverse headers, upright water wall tubes connected at their upper ends to the second transverse header, a third transverse header adjacent to the drum and connected thereto by a row of tubes, pipes connecting the respective ends of the first and third transverse headers, a longitudinal header beneath each pipe, upright water wall tubes connected at their upper ends to the longitudinal headers, tubes connecting the longitudinal headers with the pipes thereabove, headers connected to the lower ends of all the water wall tubes, and water supply connections to the last mentioned headers.

6. A steam generating furnace comprising a bank of inclined water tubes connected at each end to upright headers, a transverse steam-and-water drum arranged to supply water to the lower headers and to receive steam from the up-

per headers, a transverse header located adjacent to the lower ends of the upper headers, heat exposed tubes arranged to deliver steam to the transverse header, a second transverse header adjacent to the drum, a row of tubes connecting the second transverse header to the drum, pipes connecting the respective ends of the two trans-

verse headers, a longitudinal header beneath each pipe, upright water wall tubes connected at their upper ends to the longitudinal headers, and tubes connecting the longitudinal headers with the pipes thereabove.

GUSTAV A. REHM.
